UNITED STATES PATENT OFFICE.

CHARLES R. JOHNSON AND LOUIS P. DE FREES CARR, OF ST. MARYS, OHIO.

BARREL-HEAD FASTENING.

SPECIFICATION forming part of Letters Patent No. 337,685, dated March 9, 1886.

Application filed December 15, 1885. Serial No. 185,734. (No model.)

To all whom it may concern:

Be it known that we, CHARLES R. JOHNSON and LOUIS P. DE FREES CARR, of St. Marys, in the county of Auglaize and State of Ohio, 5 have invented certain new and useful Improvements in Barrel-Head Fastenings; and we do hereby declare the following to be a full, clear, and exact description of the invention, such as will enable others skilled in the art to which 10 it pertains to make and use it, reference being had to the accompanying drawings, which form part of this specification.

Our invention relates to an improvement in barrel-head fastenings; and it consists in a device 15 for securing the heads of the barrel in position, consisting of a piece of metal having a straight central portion, turned back parts at the ends of the straight portions, and sharp points, as will be more fully described herein- 20 after.

The object of our invention is to produce a device for use in connection with what is known as a "slack" barrel, in which flour, apples, 25 potatoes, and such materials are packed, and which devices extend over the joints in the heads of the barrel for the purpose of keeping the different parts of the heads securely in position.

Figure 1 shows a perspective of a device 30 embodying our invention. Fig. 2 is a plan view of a barrel-head, showing our device in position when in use.

In making our devices or liners we take a piece of metal, *a*, of suitable length, having 35 sharpened ends *b*, and first double the ends backward upon the body of the metal, and

then turn the ends outward at an angle to the body, as shown. The turned-back portions *c* serve to keep the central portion, *a*, from being forced closely against the side of the barrel, and hence a space is always left between the side of the barrel and the inner side of the part *a*, so that the end of a tool can be inserted between them to remove the fastenings without marring the barrel. The device 40 thus formed has its two ends driven into the inner sides of the staves at that point where the ends of the pieces which form the heads of the barrel unite with the staves in the usual manner, and has the body of the device to extend across the joints of the pieces which form 45 the heads. These pieces are held securely in position under all circumstances. As one of these devices is passed over each end of each one of the joints, the pieces which form the 50 heads are held perfectly level, and are secured in place in such a manner that no one part of the heads can be removed until the devices are withdrawn.

Having thus described our invention, we 55 claim—

A device for securing the heads of a barrel in position, consisting of a piece of metal having the central portion, *a*, turned-back parts *c*, and points *b*, substantially as shown. 60

In testimony whereof we affix our signatures in presence of two witnesses.

CHAS. R. JOHNSON.

LOUIS P. DE FREES CARR.
